ORNAMENT FOR AN AUTOMOBILE WHEEL COVER

Robert C. Nixon, Royal Oak, Mich., assignor to Chrysler Corporation, Highland Park, Mich., a corporation of Delaware

Filed Mar. 31, 1959, Ser. No. 55,286

Term of patent 7 years

(Cl. D14—30)

Fig. 1 is a front elevational view showing my new design of an ornament for an automobile wheel cover in solid lines, with a conventional wheel cover therefor shown in dotted lines for illustrative purposes only;

Figs. 2, 3 and 4 are sectional views taken on the lines 2—2, 3—3 and 4—4, respectively, of Fig. 1; and

Fig. 5 is a side elevational view of an ornament for an automobile wheel cover showing my new design.

I claim:

The ornamental design for an ornament for an automobile wheel cover, substantially as shown and described.
